ROTARY VALVE.

1,085,604.

Specification of Letters Patent.

Patented Feb. 3, 1914.

Application filed April 7, 1911. Serial No. 759,578.

To all whom it may concern:

Be it known that I, RENÉ GUILLERY, a citizen of the French Republic, residing at 103 Avenue de la République, Aubervilliers, Seine, in the French Republic, have invented certain new and useful Improvements in Rotary Valves, of which the following is a specification.

The present invention relates to a distributing system for internal combustion engines.

In the motor according to the invention each cylinder terminates in a conical chamber, the walls of which form the cylinder end and into which the explosive mixture admission pipe and the exhaust pipe for the burnt gases lead. The distribution is controlled by a hollow conical distributor having sliding contact with the walls of the corresponding chamber and which comprises therein ports which register with the admission and exhaust orifices at the proper times in the driving cycle.

In order to insure the tightness and also to prevent the pressures (of compression or of the explosion of the gaseous mixture) exerted on the distributor from retarding the sliding of the distributor on the walls of the cylinder which serve as a valve seat the mechanism which controls it is such that it maintains the contact friction between the valve and its seat constant. To this end, the mechanism connecting the distributor to the controlling member which transmits to it a continuous movement of rotation about its axis, is arranged in such a manner that if the contact friction on the walls increases there is a relative angular displacement of the driving and driven members. In consequence thereof and by means of a suitable mechanical system, the displacement referred to is transformed into a longitudinal displacement of corresponding amplitude and which, by unseating the distributor, reduces the friction to its normal value. The members then return to their original positions which permits of driving without any angular displacement the tightness of the distributor being then assured owing to the friction existing between the latter and the walls of the cylinder on which it slides. The means, to which the present invention relates, permit also of obtaining the above results whatever the direction of rotation the system may be.

In the accompanying drawing and by way of example: Figure 1 is a vertical section of the upper part of a cylinder of a motor comprising a conical distributor to which are applied the controlling devices embodying the invention. Figs. 2 and 3 show in plan two different forms of bearing plates which may be combined with balls so as to form running grooves for them. Figs. 4 and 5 are developed views of the bearing plates (Figs. 2, 3) showing their relative arrangement and their combination with balls and controlling springs.

The cylinder *a* ends in a chamber *b* of conical form the walls of which constitute the cylinder. Passages *c*, *d* for the admission of the explosive mixture and the exhaust of the burnt gases to and from the cylinder lead through the wall of the chamber *b*. The conical chamber *C* receives a hollow distributor *e*, the wall of which is provided with one or more ports *f*, and controls the admission and exhaust orifices when it is rotated on its axis. To this end, the distributor *e* is provided with a vertical spindle *g* which passes through the cylinder end *a*; a plate *h* is fixed on said shaft and its horizontal surface is provided with grooves *h'* of different pitch, constituted by any number of cavities either spherical (Figs. 3-5), the radius of which would then be greater than that of the balls *i* it receives, or oval (Fig. 2). In Fig. 5 the interposed balls *i* are shown arranged within similar cavities *h''* of another plate *j* which is arranged above and parallel to the plate *h* keyed on the shaft *g* of the distributor *e*. In Fig. 4 the plate *j* is shown provided with raised surfaces *h'''* which co-act with the balls *i*. The arrangement shown in Fig. 4 is suitable for engines which always rotate in the same direction, while the arrangement shown in Fig. 5 can be applied to engines which rotate in both directions. This plate *j* is loosely mounted on the extension *k* forming a socket for the cup shaped nut *m* which closes the chamber *h* situated above the cylinder *a* and receiving the whole of the controlling mechanism. A ball bearing disk *l* permits of the rotation of the plate *j* on the corresponding face of the nut *m* but opposes the longitudinal displacement of said plate. The shaft *g* of the distributor *e* passes freely through the extension *k* and is subjected to the action of springs *p* which

may be Belleville washers or of any other suitable kind arranged on the exterior of the motor and within the cup formed by the nut *m*. The spring *p* rests, on one hand, on 5 a washer *q* and a nut *r* of the shaft *g* of the distributor *e*, and, on the other hand, it rests on a ball bearing disk *s* pressing on the bottom of the nut *m* which closes the chamber *n* receiving the controlling members; 10 in this manner it is possible by screwing more or less the nut *r* on the shaft *g* of the distributor *e* to regulate the tension of the spring *p* which presses said distributor on the wall of the corresponding conical chamber *b* and determines the friction which insures the tightness of surfaces in contact. The motion is transmitted in any suitable manner from the driving shaft or secondary shaft to the engine to a shaft *t* provided 15 with a worm *u*, keyed thereon and engaging with the teeth cut on the plate flange *j*. The plates *h*, *j*, separated by balls *i* which are located and can move within suitable cavities *h'*, *h''* provided for this purpose, are, 20 moreover, connected by springs *v* which exert a controlling pressure on the parts when angularly displaced. In Fig. 4, for example, coiled springs *w* are provided, the ends of which are fixed to ribs *w* of the plates *h*, *j* 25 integral with the distributor *e* and the controlling member, respectively. These springs *v* act in tension which is regulated for the friction which, in order to maintain tightness must be of a sufficient degree between 30 the distributor and its seat, gives rise to a resisting couple balanced by the couple of said springs *v*.

In the modification Fig. 5 blade springs *v'* have been provided, which are held in 35 position by their ends fitting in between the conjugated faces of the plates *h*, *j*. These springs act in a manner exactly like the springs *v* and, moreover, in whatever direction the driving shaft and the distributor *e* 40 may be rotating. It will be seen that, normally, the distributor *e* being pressed on its seat owing to the spring *r* suitably regulated to this end, is driven by the controlling system; the whole of it rotates without any 45 angular displacement as if the transmission were but one element. On the contrary, when the resistance to the displacement increases, which is due to the friction of the distributor *e* on its seat increasing the said 50 distributor tends to retard the driving mechanism which continues to be actuated. The latter acts on the distributor *e* by means of its faces *h''* inclined relatively to the faces *h'* and the interposed balls *i* so as to free 55 the said distributor from its seat *b* and to diminish the friction between these members. As soon as the friction diminishes, 60 the springs *v* which have been in tension owing to the angular displacement of the 65 plates *h*, *j*, of the distributor *e* and its driv-

ing mechanism, respectively, act on said members in such a manner as to return them to their original position. In consequence thereof, the friction falls to its initial value which is sufficient to maintain tightness but 70 insufficient to produce the seizure of the contacting sliding surfaces.

The arrangement of the inclined surfaces of varying pitch *h'*, *h''* of the plates *h*, *j* between the conjugated faces of which balls *i* are interposed, permits of varying the amplitude of the longitudinal displacement of the distributor *e* relatively to its seat *b*, more rapidly than the angles of the angular displacement between the said distributor and its driving mechanism. In these circumstances, if an angular displacement of the distributor *e* relatively to its driving mechanism gives rise to a certain longitudinal displacement of the said distributor along its seat *b* then it will be found that a double angular displacement of the former will give rise to a longitudinal displacement more considerable than twice as much as in the first case. The increase in contact friction determines more rapid variations in the longitudinal displacement of the distributor or in other words, in the lifting of the distributor off its seat, which permits of overcoming the increasing friction resulting from the variations of pressures exerted on the conical distributor *e* and to return the friction to its initial value insuring a normal operation and tightness.

What I claim as my invention and desire 100 to secure by Letters Patent of the United States is:—

1. An internal combustion engine comprising a cylinder having a conical chamber at one end, orifices in the wall of said chamber to admit the supply and exhaust of the motive fluid, a hollow and conical distributor in said chamber and sliding on the wall of the latter, orifices in the distributor to control the admission and exhaust ports, a vertical shaft extending from the distributor and having a threaded end, a chamber situated above the distributor, and which receives the driving mechanism of the distributor, a cup shaped nut for closing said chamber, a hollow boss in the center of said nut projecting within said chamber and through which passes the shaft of the distributor, a nut adjustably mounted on said shaft, a spring pressing against said nut, which can be shifted on the threaded end of the distributor shaft and against a ball bearing disk at the bottom of the cup shaped nut, means for rotating said distributor and maintaining the friction constant between the distributor and its seat.

2. In an internal combustion engine, a cylinder, the end of which constitutes a conical chamber, orifices in the wall of said chamber for the admission and exhaust of the motive

fluid, a hollow conical distributer in said chamber and which has sliding contact with the wall of the latter, orifices in the distributer for controlling the admission and exhaust orifices, a vertical shaft extending from the distributer beyond the distributer and threaded at its upper end, a cup shaped nut supporting said distributer, a hollow boss in the center of said nut and through which passes the shaft of the distributer, a spring pressing against a nut provided on the upper end of the distributer shaft, and against a ball bearing disk at the bottom of the cup shaped nut, a chamber situated above the cylinder and on the wall of which the said nut is fixed, a worm in said chamber to be driven by the driving shaft, a

toothed plate meshing with said worm and rotating on the boss extending said nut, inclined faces on said plate, a corresponding plate arranged parallel to the first plate, and keyed on the distributer shaft, inclined faces on said plate, balls interposed between the faces of the plates and springs connecting the latter to insure the rotation of the distributer and to maintain the friction constant between the seat and said distributer. 20 25

In testimony whereof, I affix my signature in presence of two witnesses.

RENÉ GUILLERY.
